Application filed October 30, 1916. Serial No. 128,630. Term of patent 3½ years.

To all whom it may concern:

Be it known that I, GUSTAVE M. FAUSER, a citizen of the United States, residing in the city of New York, county of New York, and State of New York, have invented a new, original, and ornamental Design for a Border for Wall-Paper; and I hereby declare the following to be a description of the same in such terms as will enable anyone skilled in the art to which it appertains to make and use the same, reference being had to the accompanying drawings.

The figure of the drawing is a plan view of a section of wall paper border illustrating my new design.

The design shows an upper strip A, and panels B B, in each of which panel is a vase C, suspended from the strip A. At the base of each panel is a bunch of flowers D. Between the panels are figured spaces E E.

The design as shown is intended to be repeated or matched out upon either side indefinitely, as is usual in such cases.

What I claim is:—

The ornamental design for a border for wall paper as shown and described.

GUSTAVE M. FAUSER.
